UNITED STATES PATENT OFFICE.

EMIL BANICK, OF NEWARK, NEW JERSEY.

PORTABLE ELECTRIC SAFETY-LAMP.

1,068,836.

Specification of Letters Patent. Patented July 29, 1913.

Application filed December 9, 1912. Serial No. 735,770.

To all whom it may concern:

Be it known that I, EMIL BANICK, a citizen of the United States, residing at Newark, in the county of Essex and State of New Jersey, have invented certain new and useful Improvements in Portable Electric Safety-Lamps, of which the following is a specification, reference being had to the accompanying drawings.

10 This invention relates to new and useful improvements in portable electric safety lamps, the object of the invention being to provide a handy, safe and convenient article for the purpose and which is particularly applicable for use in dangerous situations such as coal or other mines, powder mills, magazines, chemical laboratories and the like.

Another object of the invention is to provide an electric safety lamp of the above 20 character which will possess advantages in points of efficiency and durability, is inexpensive to manufacture and at the same time is simple in construction and operation.

25 With the above and other objects in view, the invention consists in the novel features of construction and combination and arrangement of parts hereinafter more fully 30 described, pointed out in the claims, and shown in the accompanying drawing, in which—

Figure 1 is a front elevation of an electric safety lamp constructed in accordance with 35 my invention, parts being broken away and in section. Fig. 2 is a transverse sectional view. Fig. 3 is a vertical sectional view through the casing. Fig. 4 is a vertical sectional view through the entire device, and 40 Fig. 5 is a detail vertical sectional view illustrating the construction of the valve.

Referring more particularly to the drawings, 1 indicates the case or receptacle which is provided with a suitable handle 2 where- 45 by the same may be readily transported from place to place. Arranged within the casing 1 is a battery 3 which is spaced from the front wall of the case by means of blocks 4 arranged at the top and bottom of the bat- 50 tery and disposed between the battery and the front wall of the casing. Secured to the battery casing and projecting upwardly therefrom are the supporting members 5 which are adapted to support the binding 55 posts 6. Arranged within the casing and disposed between the battery and the front

wall of the casing is an angular guard plate 7. Secured to the front wall of the casing upon the inner side thereof and having their inner ends overlapping, within the 60 angular guard plate 7, are the contact plates 8 and 9, said plates being suitably connected to the binding posts 6 by the positive and negative wires 10 and 11.

Mounted in the front wall of the casing 65 and arranged just above the guard plate 7 is a lamp socket 12, in which is arranged the incandescent lamp 13. The socket 12 is suitably connected to the contact plates through the medium of the negative wire 70 11. Secured to the front wall of the casing and arranged around the lamp 13 is a reflector 14, and slidably mounted within an opening of the reflector at the lower side thereof, is a rod 15, the inner end of which 75 is disposed through an opening in the front wall of the casing and adapted to engage the free ends of the contact plates 8 and 9 when the glass 16 is arranged in the front of the reflector, thus closing the circuit. It 80 will be apparent that by having the rod 15 slidably mounted and the inner end thereof engaging the overlapping ends of the contact plates, that when the glass 16 is placed within the front of the reflector 14, it will 85 press inwardly upon the rod 15 and engage the inner ends of the contact plates so that the circuit will be closed, but in case the glass should be broken, the resiliency of the 90 plates will force the rod outwardly, thus 95 disengaging the overlapping ends of the contact plates and opening the circuit to extinguish the lamp. Thus it will be seen that should there be any explosive gases within the room, or any danger of any explosive material coming in contact with the light, the danger of an explosion will be eliminated by the instantaneous extinguishing of the lamp.

The upper end of the battery casing is 100 provided with a suitable opening in which is arranged a vent pipe 17, and slidably mounted within the vent pipe is a stem 18, the lower end of which is secured to the circular valve member 19. It will be apparent 105 that should the valve casing be tipped at an angle or upside down, the upper end of the valve 19 will be disposed within the lower end of the pipe 17 to prevent any escape of the electrolyte. It will also be seen that 110 when the electrolyte becomes low within the battery casing, the height thereof within the

casing will be indicated by the stem 18 which projects upwardly through the pipe 17.

From the above description taken in connection with the accompanying drawings, it will be apparent that I have provided a simple and durable electric safety lamp which can be easily transported from place to place and at the same time is simple in construction and inexpensive to manufacture.

In the operation of my improved safety lamp, the rod 15 is mounted within the openings in the reflector and the front wall of the casing and has its inner end coming in contact with the free end of the plate 9. The rod is then pressed inwardly until the plate 9 engages the free end of the plate 8. The glass 16 is then arranged within the reflector so that the same may be pressed against the outer end of the rod 15 retaining the same in its operative position so as to keep the circuit closed and the lamp 13 lighted. If the reflector glass is accidentally broken, the resiliency of the plate 9 will push the rod 15 outwardly, thus disengaging the plates 8 and 9 and breaking the circuit which will immediately extinguish the lamp before the obstruction which broke the glass can reach the lamp to break it also. Thus by the time the lamp is broken, all danger of ignition of explosive material will be obviated. It will be understood that the glass 16 may be a frosted one for diffusing light in order to light up a given inclosed space, but if the light is to be used for revealing objects in the distance, a clear glass is used.

While I have shown and described the preferred form of my invention, it will be obvious that various changes in the details of construction and proportion may be resorted to for successfully carrying my invention into practice without sacrificing any of the novel features or departing from the scope thereof.

What I claim is:—

1. In a device of the character described, the combination of a casing, a battery arranged within said casing and a lamp mounted in the front wall of the casing, a reflector surrounding said lamp and glass mounted in the front of the reflector, resilient contact plates mounted in the casing, a horizontally disposed rod slidably mounted in the front of the casing and pressed inwardly by the glass in the reflector to normally retain the contact plates in an operative position to close the circuit between the lamp and the battery, whereby when the

glass is broken the contact plates will be released to break the circuit between the lamp and the battery.

2. In a device of the character described, the combination of a casing, a battery arranged within said casing, a lamp mounted in the front wall of the casing, overlapped resilient contact plates within the casing, connections between the battery and the contact plates, connections between the contact plates and the lamp, a stationary reflector surrounding the lamp, a destructible member in front of the reflector, and means engaged with the destructible member and with one of the contact plates to retain the latter in engagement with the other contact plate and thereby close the circuit while the destructible member is in position.

3. In a device of the character described, the combination of a casing, a battery arranged within the casing, overlapped resilient contact plates, connections between the battery plates, a lamp mounted in one wall of the casing, a reflector surrounding the lamp, a destructible member in front of the reflector, connections between the contact plates and lamp, and means engaged against the destructible member and against one of the contact plates to retain the same in engagement with the other contact plate, said means being adapted to be forced outwardly by the contact plates and thereby allow separation of the same to break the circuit upon destruction of the destructible member.

4. In a device of the character described, the combination of a casing, a battery within the casing, a stationary lamp mounted in the casing, a stationary reflector around the lamp, a destructible member outwardly of the reflector, a pair of normally spaced apart resilient contact plates within the casing, connections between the battery and the contact plates, connections between the contact plates and the lamp, and a slidable horizontal rod for forcing one of the contact plates against the other plate to complete the circuit, said rod being retained in position by the destructible member, whereby said rod will be forced outwardly by the contact plates, upon destruction of the destructible member.

In testimony whereof I hereunto affix my signature in the presence of two witnesses.

EMIL BANICK.
